APPARATUS FOR PRODUCING SHINGLE STRIPS

Application filed May 15, 1929. Serial No. 363,322.

This invention relates to roofing elements in the form of shingle strips and is particularly concerned with the production of roofing strips from continuous sheets of flexible roofing material.

The principal object of the invention resides in the production of roofing strips of generally rectangular shape having curvilinear exposed butt-edges so that when a number of such strips are laid on a roof, an attractive ornamental appearance approximating that of thatched roofs will be produced.

A further object of the invention is to provide improved means for severing strips of this character from continuous sheets of roofing material.

Still a further object of the invention is to provide the strips with means for effecting an interlock between adjacent strips in each horizontal course on the roof, and according to the preferred form of the invention, to form the cooperating interlocking portions in the shingle strips simultaneously with the severance of the strips from the sheet of roofing.

In accordance with the invention, the sheet is slit longitudinally thereof along a harmonic curvilinear path, defined by a circular knife mounted on a rotatable cylinder, the knife lying substantially entirely in one plane extending at an inclination to the axis of the cylinder, so that as the cylinder rotates the knife will follow a harmonic sinuous course.

The curvilinear slit thus made in the sheet provides complementary sections from each of which separate elements having curvilinear butt-edges may be severed. In order to form the end edges of the strips and complete the severance thereof from the sheet, straight parallel cutting blades are affixed to the cylinder on opposite sides of the circular knife at diametrically opposed points.

The invention will be more clearly understood from the following detailed description and from the accompanying drawings.

In the drawings,

Figure 1 is a view of the cutting cylinder with the knives mounted thereon,

Figure 2 is a geometric development illus-

trating the relation of the circular knife to the rotatable cutting cylinder,

Figure 3 is a fragmentary view in plan showing the path evolved by the circular knife of Figure 2 during half a revolution of the cylinder,

Figure 4 is a plan view showing the layout of a number of shingles in the sheet when operated upon in accordance with the invention, and

Figure 5 is a showing of a section of a roof with several courses of shingle strips designed in accordance with the invention, laid thereon.

In practicing the invention, I prefer to use a sheet of roofing of such a width as will provide two pairs of complementary series of strips, as shown in Figure 4, the material for each of said series being slit longitudinally along a harmonic curvilinear path in accordance with the novel concept of the invention. In order thus to slit the sheet the cutting cylinder is mounted with its longitudinal axis extending transversely of the sheet, the latter being fed continuously between the cutting cylinder and a cooperating bed roll, (not shown). As will be evident, the diameter of the cutting cylinder will depend upon the length of the shingle strips desired and the number of strips to be severed longitudinally of the sheet during each complete revolution of the cylinder. In actual practice, I prefer to use a cutting cylinder of such a diameter that the circular cutting knife mounted thereon will traverse during each revolution thereof, a linear distance corresponding to the length of the strips desired.

The sheet material indicated at "S", from which the shingle strips are severed in accordance with my invention, may comprise the usual form of asphalt saturated and coated and mineral surfaced felt, or similar waterproof and preferably flexible material.

As shown in Figure 1, the rotatable cylinder, indicated by the numeral 20, has mounted thereon, the circular slitting knives 21 and 22, each of these knives lying in a single plane which extends at an inclination to the longitudinal axis of the cylinder. As will be clear from Figures 2, 3 and 4, rotation of the cylin-

der will cause the knives 21, 22, to follow harmonic curved paths, as indicated at 21a, 22a, respectively, the amplitude of which will depend upon the angle of inclination of the planes in which the knives lie, respectively, to the axis of the cylinder. The wave length of the curves thus produced will manifestly be equal to the circumference of the knife blades. By thus utilizing the mathematical principle governing the surface development of the intersection of a circle lying in a plane at an angle to the axis of a cylinder rotating on a fixed axis, I provide a very advantageous method of cutting sheet material of the character of prepared roofing, along sinuous lines, and thereby avoid the necessity of employing warped or skewed knives to cut shingles of this character. The arrangement as thus described, renders possible a rapid, continuous operation upon the sheet without any tendency of the sheet to weave or buckle under the action of the cutting knives.

Where two circular slitting knives as above described, are employed, I prefer to have the plane of the two knives extending in opposite directions with respect to the axis of the cylinder. In this way the tendency of the sheet to weave under the action of the knives is further eliminated. The use of two circular knives as illustrated, also makes it possible if so desired, to have one of the slits 21a, 22a, of different amplitude from the other, merely by positioning the knives at different angles with respect to the axis of the cylinder.

The curvilinear slits 21a and 22a as thus formed in the sheet, each produce the complementary butt-edges of a series of shingles on either side of the respective slits. As will be understood from what has been said above and from the showing in the drawings, the sheet is of sufficient width to produce two pairs of longitudinal series of strips from the sheet, the separate pairs being separated from each other along a slit 23a, formed longitudinally in the sheet through the middle thereof, by a circular knife 23 extending circumferentially about the cylinder, intermediate the knives 21 and 22.

The cylinder is also provided with diametrically opposed cutting blades 24 and 25, parallel to the axis of the cylinder and extending on opposite sides of the circular knife 21, and with a similar pair of diametrically opposed blades 26 and 27 lying on opposite sides of the circular knife 22, the knives 24 and 26 being slightly offset from each other circumferentially of the cylinder and the knives 25 and 27 being similarly offset from each other. The knives 24, 25, 26 and 27 form the transverse cuts in the sheet as shown at 24a, 25a, 26a and 27a respectively, these cuts defining the end edges of adjacent shingles in each longitudinal series cut from the sheet.

I provide also means for simultaneously

forming the shingle strips with slits adjacent the ends thereof, which slits are adapted to cooperate in the laying of the strips on the roof to interlock adjacent elements in each horizontal course. To this end, the cylinder 20 is provided on alternately opposite sides of each of the knives 24, 25, 26 and 27, with short knife blades 28, parallel to the knives 24 to 27 and spaced a slight distance therefrom, one extremity of the blades 28 being in close contact with the circular knives 21 and 22. The cylinder is also provided on the opposite sides of the knives 24 to 27 with double angular cutting blades 29 lying in a direction generally at right angles to said blades. Each of the blades 29 has one of its elements intersecting knives 24 to 27 at a point in alignment with outer end of the blades 28 and extending at an angle toward the knives 21, 22; another and oppositely inclined element; and finally a short straight element parallel to the knives 24 to 27 and terminating a short distance from the knives 21 and 22. The blades 28 and 29 as thus disposed on the cylinder, form the slits 28a and 29a respectively in the several longitudinal series of elements in the manner shown in Figure 4 of the drawings. Preferably also, the knives 24 to 27 terminate at a slight distance from the knives 21, 22, and additional blades are fixed on the cylinder to form slits 30a, 31a, which together with the slits 21a, 22a, complete the formation of small cutout pieces 32 in the sheet on alternately opposite sides of the slits 21a, 22a, as clearly shown in Figure 4.

The shingles 33 as thus produced from the sheet of roofing material S, may be laid in successive overlapping courses on a roof in the usual manner with adjacent ends of the shingles in each course overlapping one another, as shown in Figure 5, the slits 28a on one end of the shingle being engaged with the cooperating slit 29a on the adjacent edge of the adjacent shingle, to form an interlock between the two, as at 34, whereby to avoid lifting or blowing of the exposed portions of the shingle under the action of the wind. As will be observed from Figure 5, the vertical extent of exposure at all corresponding points on the roof, is alike, although this varies harmonically in a horizontal direction with the contour of the exposed butt edges. It will be understood, however, that at some portions of the roof the succeeding courses may be exposed to different extents than at other portions of the roof so as to obtain a diversified appearance in the finished roof. It will be noted also that by virtue of the overlapping and interlocking arrangement of adjacent ends or adjacent shingles in each course, not only in the tendency to lifting up or blowing up of exposed portions avoided, but that also the arrangement provides a greater barrier to the entrance of water between the joints of adjacent shingles.

I claim as my invention :

1. In mechanism for cutting sheet material to sever therefrom roofing elements of curvilinear butt-edge configuration, the combination of a rotatable cylinder and a circular knife fixed to the surface of the cylinder, said knife lying entirely in a single plane extending at an angle to the axis of said cylinder, and cutting blades fixed to the surface of the cylinder and extending in parallelism with the axis thereof on opposite sides of said circular knife, said blades being located at substantially diametrically opposed points on the cylinder.
2. In mechanism for cutting sheet roofing material to sever therefrom roofing elements of curvilinear butt-edge configuration, a combination of a rotatable cylinder and a plurality of spaced circular knives fixed to the surface of the cylinder, each of said knives lying entirely in a single plane extending at an angle to the axis of the cylinder, and a plurality of pairs of cutting blades fixed to the surface of the cylinder and extending in parallelism with the axis thereof, the blades of each pair lying on opposite sides of one of said circular knives and being located at substantially diametrically opposed points on the cylinder.
3. In mechanism for cutting sheet roofing material to sever therefrom roofing elements of curvilinear butt-edge configuration, a combination of a rotatable cylinder and a plurality of spaced circular knives fixed to the surface of the cylinder, each of said knives lying entirely in a single plane extending at an angle to the axis of the cylinder, and a plurality of pairs of cutting blades fixed to the surface of the cylinder and extending in parallelism with the axis thereof, the blades of each pair lying on opposite sides of one of said circular knives and being located at substantially diametrically opposed points on the cylinder, one of the blades of each pair being in substantial alignment with one of the blades of the other pair.

Signed at Los Angeles, in the county of Los Angeles and State of California, this 7th day of May, A. D. 1929.

HENRY R. WOOD.
